COMPRESSOR

Jacob G. Aldinger, York, Pa., assignor to York
Ice Machinery Corporation, York, Pa., a corpo-
ration of Delaware

Application May 29, 1935, Serial No. 24,128

14 Claims. (Cl. 230—22)

This invention relates to compressors and particularly to unloading means therefor. The present application relates to an improvement on the structure of my prior application Serial No. 5 715,548, filed March 14, 1934, and an important feature of improvement, particularly for the larger size compressors, is the use of a separate distributing valve to control the differential piston motor which actuates the unloading valve. 10 In this way a single distributing valve can be used to operate simultaneously a plurality of unloading valves in a compressor having a plurality of working spaces and simultaneous rapid actuation of the various unloading valves can be assured. 15 Another advantage of the invention is that a single pilot valve, for example, an electrically actuated pilot valve, and a single distributing valve controlled thereby and in turn controlling the unloading valve motor, can be used with any 20 required number of cylinders, without change in their dimensions or capacity.

A preferred embodiment of the invention will now be described in connection with the accompanying drawings, in which,—

25 Fig. 1 is a vertical sectional view transverse to the axis of the crank shaft. The planes of section are indicated by line 1—1 on Fig. 2.

Fig. 2 is an elevation of a two-cylinder compressor with the invention applied.

30 Fig. 3 is a section through the pilot valve mechanism showing this in position to load the compressor.

Fig. 4 is a similar view showing the pilot valve in position to unload the compressor.

35 Referring first to Fig. 2, it will be observed that the two cylinders are formed in a single casting which includes the cylinders 11, there being a cored enlargement 12 encircling the upper portions of the cylinders and enclosing 40 water jackets 13, and a cored enlargement 14 encircling the lower portions of the cylinders and enclosing an intake manifold 15. The suction connection indicated at 16 leads to the manifold 15. A series of intake ports 17 leads from the 45 manifold 15 through the cylinder walls. The ports 17 are so located as to communicate with slots 18 formed in the trunk piston 19.

The trunk piston 19 carries the inlet valve 21, indicated as of the poppet type, and conforming 50 to known practice. 22 indicates the usual safety head, there being a safety head mounted in each cylinder and held in its lower or seated position by a coil compression spring 23 interposed between it and the fixed cylinder head 24. The 55 fixed cylinder head 24 is common to the two

cylinders and encloses a space 25 which is in communication with the compressor discharge connection, not shown.

The discharge valves 20 of the compressor are of the automatic type and are mounted within 5 respective safety heads 22 as usual. An unloading passage 26 formed in bosses 27 on the main cylinder casting connects the intake manifold 15 with the unloading ports 28. These are located in each cylinder wall at part stroke and 10 their distance from the head end determines the degree of unloading effected when the ports are open.

A cylinder housing 29 with head 30 is bolted 15 to the main cylinder casting of the compressor, as indicated in Fig. 1, and receives and guides the unloading valve element, which takes the form of a combined differential piston and poppet valve. Formed in one piece are a relatively large piston head 31, a somewhat smaller trunk or 20 body 32, and a valve head 33 coacting with the seat 34. The seat 34 is located to control flow through the ports 28 and the flow is cut off when the valve member 33 engages the seat 34. The head 31 is provided with piston packing rings 35 25 of conventional form, and similar packing rings 36 are provided on the trunk portion 32.

A stem 37 is threaded in the head 30 and may be turned by wheel 38. A suitable packing gland is provided, as shown. When the stem 37 is 30 screwed in it forces the valve 33 against the seat 34, holding the unloading valve in its closed position. Under normal conditions, however, the stem 37 is in its outer position, as shown in Fig. 1, leaving the unloading valve free to make its 35 opening excursion.

Mounted on the side of the compressor is the body 41 of the distributing valve. A convenient way of mounting it is to support it on the pipe connection 42 which connects the interior of the 40 housing 41 with the intake manifold 15. The housing 41 is bored axially to provide a seat for a balanced piston valve having two valve heads 43 and 44. The supply port 45 always communicates with the space within the valve chamber 45 between the heads 43 and 44. Pressure fluid taken from the discharge space 25 within the head structure 24 is conducted by the pipe 46 and filter 47 to the port 45. The pipe 42 which is at suction pressure communicates directly with the 50 space above the upper valve head 44 and communicates by way of port 48 with the space below the lower head 43. Consequently the ends of the piston valve are both exposed to suction pressure and the valve is perfectly balanced. 55

- Formed through the housing 41 are connections 51 and 52 which lead to ports in the valve chamber controlled by the valve heads 43 and 44. When the piston valve is in its upper position (see Fig. 3) the ports 52 are connected to the supply port 45 and the ports 51 are connected by way of passage 48 and pipe 42 with the suction manifold 15. When the piston valve is in its lowermost position (Fig. 4) the supply connection 45 is connected with the ports 51 and the ports 52 are connected by way of pipe 42 with the suction manifold 15.
- The connections 51 communicate by way of branch pipes 53 with the ports 54 which lead to the small annular working spaces surrounding the trunks 32 of the unloading valves, it being understood, as indicated in Fig. 2, that there is an unloading valve for each cylinder of a multi-cylinder compressor.
- Leading from each of the ports 52 is a pipe 55 which leads to a port 56. The port 56 communicates with the working space at the outer end of the corresponding unloading valve, that is, the space on the outer side of the piston head 31. The balanced piston valve is urged in an upward direction by a coil compression spring 57 and may be forced downward against the urge of that spring by a piston 58 larger than the piston valve and working in a cylinder formed in the upper end of the housing 41. This piston is provided with a bleed port 59 and the lower face of the piston 58 is subject to compressor suction pressure, that is pressure in the manifold 15 because of the direct connection afforded by the pipe 42.
- The lower end of the housing 41 is enclosed by a cap 61 which also offers a seat for the spring 57. The upper end of the housing 41 is closed by a cap 62 which contains a small chamber 63 supplied with pressure fluid at the discharge pressure of the compressor by a branch passage 64 leading from the passage 45. A pin valve 65 coacting with a seat 66 controls flow from the chamber 63 to the space above the piston 58. The valve 65 is normally closed but may be opened by the excitation of a winding indicated by the numeral 67 applied to its enclosing casing. The terminals of the winding are indicated at 68 and 69 and the circuit through the winding may be controlled by any means, not shown, preferably a switch responsive to some physical condition affected by the operation of the compressor, for example, pressure in a receiver fed by the pressure, suction pressure, or where the compressor is included in a refrigerating circuit, the temperature created by the operation of the system.
- It is important to observe that the capacity of the port through the seat 66 exceeds the capacity of the bleed port 59.

60 Operation

When the pin valve 65 closes against seat 66 the port 59 will cause equalization of pressures above and below the piston 58, and the spring 57 will shift the balanced piston valve to its uppermost position (see Figs. 1 and 3). Under these conditions fluid compressed by the compressor flows by way of pipe 46, filter 47, port 45, ports 52, pipes 55 and ports 56 to the working spaces 70 at the outer sides of the large piston heads 31 of the unloader valves. Consequently the unloader valves close, as shown, and each piston 19 of the compressor is effective throughout its entire stroke. The closing movement of the unloader 75 valve is facilitated by reason of the fact that the

small annular working space to the right of the head 31 is exhausted by way of port 54, pipe 53, ports 51, passage 48 and pipe 42 to the suction manifold 15 of the compressor.

If the winding 67 be excited the valve 65 will be lifted from the seat 66, admitting pressure fluid at the pressure of compressor discharge, by way of pipe 46, filter 47, passage 64, through valve seat 66, against the upper side of piston 58. Since the pressure fluid is supplied at a rate in excess of the vent capacity of port 59 the piston 58 will be forced downward, shifting the piston valve to its lowermost position (Fig. 4), the space on the outer or left hand side of piston 31 is vented to the suction connection, while the annular space to the right of the piston head 31 is subject to discharge pressure. Consequently, the unloading valve is held in its outer or open position and the compressor piston 19 is ineffective until it has overtraveled the ports 28, because until it overtravels these ports the working space is connected by way of ports 28 and passage 26 with the intake passage 15 of the compressor.

It should be observed that a single winding 67 and a single piston valve actuated thereby control a plurality of unloading valves in unison. A standardized winding and a standardized piston valve can be used with compressors of various sizes and compressors having various numbers of cylinders. Furthermore the shifting of the unloading valves for the various cylinders will be simultaneous and the unloading valves will be held positively in their open and closed positions. It is important to observe that the effective area on the outer side of the piston 31 greatly exceeds the area of the end of valve 33 exposed to cylinder pressure.

While one specific embodiment of the invention has been described in considerable detail, the fact that various modifications are possible is fully recognized, and the scope of the invention is to be defined solely by the claims.

What is claimed is,—

1. The combination of a compressor having a working space; unloading means therefor; a reversible piston motor for shifting said unloading means between active and inactive positions; a distributing valve shiftable to reverse said piston motor; a piston and opposed yielding means for shifting said distributing valve; and means for controlling the shifting of the last-named piston; said means comprising a valve and a port of smaller flow capacity, one controlling the supply and the other discharge of pressure fluid to and from the last-named piston, and means for opening and closing the last-named valve.

2. The combination of a compressor having a working space; unloading means therefor; a reversible piston motor for shifting said unloading means between active and inactive positions; a distributing valve shiftable to reverse said piston motor; a piston and opposed yielding means for shifting said distributing valve; and means for controlling the shifting of the last-named piston, said means comprising a valve and a port of smaller flow capacity, one controlling the supply and the other the discharge of pressure fluid taken from the discharge of the compressor to and from the last-named piston, and means for opening and closing the last-named valve.

3. The combination of a compressor having a working space; an unloading valve therefor urged in an opening direction by fluid pressure in the working space; a reversible differential piston motor for opening and closing said unloading

valve, the piston of said motor having a larger effective area in a closing than in an opening direction; a distributing valve shiftable to reverse said piston motor; a piston and opposed yielding means for shifting said distributing valve; and means for controlling the shifting of the last-named piston, said means comprising a valve and a port of smaller flow capacity, one controlling the supply and the other the discharge of pressure fluid taken from the discharge of the compressor to and from the last-named piston, and means for opening and closing the last-named valve.

4. The combination of a compressor having a working space; an unloading valve therefor urged in an opening direction by fluid pressure in the working space; a reversible differential piston motor for opening and closing said unloading valve, the piston of said motor having a larger effective area in a closing than in an opening direction; a distributing valve shiftable to reverse said piston motor; a piston and opposed yielding means for shifting said distributing valve; and means for controlling the shifting of the last-named piston, said means comprising a valve and a port of smaller flow capacity, one controlling the supply and the other the discharge of pressure fluid to and from the last-named piston, and means for opening and closing the last-named valve.

5. The combination of a compressor having a plurality of working spaces; individual unloading means for corresponding working spaces; reversible piston motors, one for shifting each unloading means between active and inactive positions; a single distributing valve connected to reverse said piston motors in unison; a piston and opposed yielding means for shifting said distributing valve; and means for controlling the shifting of the last-named piston, said means comprising a valve and a port of smaller capacity, one controlling the supply and the other the discharge of pressure to and from the last-named piston, and means for opening and closing the last-named valve.

6. The combination of a compressor having a plurality of working spaces; independently operable unloading valves one for each working space, said valves being urged in an opening direction by pressure in the corresponding working space; reversible differential piston motors each arranged to open and close a corresponding unloading valve, the pistons of such motors having a larger effective area in a closing than in an opening direction; a single distributing valve connected to reverse said motors in unison; a piston and opposed yielding means for shifting said distributing valve; and means for controlling the shifting of the last-named piston, said means comprising a valve and a port of smaller capacity, one controlling the supply and the other the discharge of pressure to and from the last-named piston, and means for opening and closing the last-named valve.

7. The combination of an unloading device for a compressor or the like; a reversible double-acting piston motor for shifting said device between loading and unloading positions; a balanced piston valve of the inlet and exhaust type for reversing said motor; yielding means urging said valve in one direction; a piston for forcing said valve in the opposite direction; and means for controlling the actuating pressure on the last-named piston, said means comprising a valve and a port of relatively smaller capacity,

one controlling supply and the other discharge of pressure fluid, and means for opening and closing the last-named valve.

8. The combination of an unloading device for a compressor or the like; a reversible double-acting piston motor for shifting said device between loading and unloading positions; a balanced piston valve of the inlet and exhaust type for reversing said motor; yielding means urging said valve in one direction; a piston for forcing said valve in the opposite direction; and means for controlling the actuating pressure on the last-named piston, said means comprising a valve and a port of relatively smaller capacity, one controlling supply and the other discharge of pressure fluid, and electrically actuated means for opening and closing the last-named valve.

9. The combination of a compressor having a working space; unloading means therefor; a reversible piston motor for shifting said unloading means between active and inactive positions; a distributing valve shiftable to reverse said piston motor; a piston and opposed yielding means for shifting said distributing valve; and electrically controlled means for establishing and exhausting an operating pressure on the last-named piston.

10. The combination of a compressor having a working space; unloading means therefor; a reversible piston motor for shifting said unloading means between active and inactive positions; a distributing valve shiftable to reverse said piston motor; a piston and opposed yielding means for shifting said distributing valve; and means for alternatively subjecting the last-named piston to pressure derived from the compressor discharge, and to compressor suction pressure.

11. The combination of a compressor having a working space; an unloading valve therefor urged in an opening direction by fluid pressure in the working space; a reversible differential piston motor for opening and closing said unloading valve, the piston of said motor having a larger effective area in a closing than in an opening direction; a distributing valve shiftable to reverse said piston motor; a piston and opposed yielding means for shifting said distributing valve; and means for alternatively subjecting the last-named piston to pressure derived from the compressor discharge, and to compressor suction pressure.

12. The combination of a compressor having a working space; an unloading valve therefor urged in an opening direction by fluid pressure in the working space; a reversible differential piston motor for opening and closing said unloading valve, the piston of said motor having a larger effective area in a closing than in an opening direction; a distributing valve of the balanced piston type shiftable to reverse said piston motor; and fluid pressure operated means for shifting said distributing valve.

13. The combination of a compressor having a plurality of working spaces; independently operable unloading valves one for each working space, said valves being urged in an opening direction by pressure in the corresponding working space; reversible differential piston motors each arranged to open and close a corresponding unloading valve, the pistons of such motors having a larger effective area in a closing than in an opening direction; a single distributing valve connected to reverse said motors in unison; and means for shifting said distributing valve.

14. The combination of a compressor having a plurality of working spaces; independently op-

5 erable unloading valves one for each working space, said valves being urged in an opening direction by pressure in the corresponding working space; reversible differential piston motors each arranged to open and close a corresponding unloading valve, the pistons of such motors having a larger effective area in a closing than in

an opening direction; a single distributing valve connected to reverse said motors in unison; a piston and opposed yielding means for shifting said distributing valve; and means for alternately establishing and dissipating an operating pressure on the last-named piston. 5

JACOB G. ALDINGER.
